DRYING OVEN

Robert R. Lundy, South Bend, Ind.

Application January 12, 1934, Serial No. 706,348

8 Claims. (Cl. 34—19)

This invention relates to improvements in drying ovens and particularly to drying ovens for performing a siccative action on objects of relatively large size, and has for its principal object the provision of drying or baking ovens for performing a siccative action on single objects, or small groups of objects, individually.

A further object resides in the provision of drying or baking ovens which may be applied to one or more of a train of articles of manufacture moving on a continuous track, without affecting the siccative action on other articles in the train or interrupting the progress of the train.

15 A still further object of the invention lies in the provision of a drying or baking oven which completely encloses the article to be treated, in either a stationary or moving position, and prevents or retards the escape of heated, or otherwise treated, air or gas, from the oven during the siccative action, thus reducing the cost of the operation and preventing the deposit of dust or foreign matter on the wet surface of the object.

An additional object of this invention resides 25 in the provision of a drying or baking oven whereby a siccative action may be obtained at a low operating cost because of simplicity of article processing and oven handling equipment.

Another object resides in the provision of a 30 drying or baking oven which completely encloses the article to be treated, in either a stationary or moving position, thereby maintaining a uniform temperature in the enclosure regardless of air conditions outside of the oven.

35 Other objects and advantages of the invention will appear as the description proceeds. In the accompanying drawings I have illustrated one mechanical embodiment of the idea of the invention and several slightly modified forms, together with suitable methods of operation thereof. The drawings, however, are for the purpose of illustration only and are not to be considered as limiting the invention, the scope of which 40 is to be measured entirely by the scope of the subjoined claims.

In the drawings:

45 Figs. 1a and 1b illustrate the application of my improved drying oven to a production line carrying objects such as automobile bodies;

Fig. 2 is a vertical elevational view of one form of my improved drying oven;

Fig. 3 is a transverse sectional view taken on the line 3—3 of Fig. 2;

50 Fig. 4 is a fragmentary view similar to Fig. 2

showing a somewhat modified form of the device of the invention;

Fig. 5 illustrates a somewhat different application of my improved drying oven to a production line carrying objects such as automobile 5 bodies; from the application illustrated in Fig. 1;

Fig. 6 is an end elevational view of a modified form of my improved drying oven and means for supporting the same;

Fig. 7 is a side elevational view of the drying 10 oven illustrated in Fig. 6.

Fig. 8 is a sectional view of a plant building showing a different application of my improved drying oven from that illustrated in Figs. 1a and 1b and 5;

Fig. 9 is an elevational view of a drying oven especially adapted for the application illustrated in Fig. 8; and

Fig. 10 is a fragmentary elevational view of a modified form of drying oven showing a movable 20 hinged end or side therefor.

Referring to the drawings in detail, and particularly to Figs. 1a and 1b, the numeral 10 designates a continuous track laid on the floor 11 and upon which a series of trucks 12, supported 25 thereon by suitable wheels or rollers 14 is adapted to travel.

Carried upon each truck is an article of manufacture such as an automobile body 15. In the application of the device as illustrated, the article 30 15 receives a coating such as paint or lacquer in the spray booth 18 and emerges from the booth with the coating in a "wet" or solvent condition. This wet coating must receive siccative action 35 before the article can be handled and the next step of the manufacturing process begun.

In order to accomplish the siccative action of these wet coated articles in the least possible time and at the minimum expense I have provided 40 a plurality of special drying ovens 20. The number of ovens required to carry out the method of my invention depends upon, and is largely determined by, three factors, namely, the length of time required for the siccative action, the speed with which the trucks carrying the coated articles 45 pass over the track, and the number of trucks upon a given length of track. Having first determined the maximum time required for the siccative action of the coating of the type under consideration, a length of track is laid off, as 50 illustrated in Figs. 1a and 1b, such that a truck carrying a coated article will pass from one end to the other, of the measured length of track in the time specified, the number of trucks ordinarily supported upon this length of track is then 55 de-

terminated. To this number must be added enough reserve ovens to render the process continuous in placing the ovens over the articles and removing them therefrom in addition to a small number of 5 "spare" ovens for use in case one or more of the ovens should develop mechanical troubles which would necessitate its temporary removal from service.

As further illustrated in Figs. 1a and 1b, the 10 length of track specified above is provided with an overhead trolley 22 embodying three electrical conductors 22a, 22b, and 22c carried by suitable supports 23 of insulating material. While I have 15 illustrated and described an overhead, three-bar trolley, it is to be understood that the invention is in no way limited to this type of electrical conductor and that any other suitable type, such as a "third-rail" type, may be used if desired.

At a distance above the above mentioned length 20 of track, somewhat greater than twice the height of each of the drying ovens 20, I have provided a suspension track 24 secured to the ceiling 25 by suitable supports 26. This suspension track 24 has a generally rectangular cross section and is 25 provided with a slot extending continuously along the under side thereof. At each end of the suspension track, I have provided a hoisting mechanism generally indicated at 27 and 29. Each hoisting mechanism comprises a pair of 30 flexible cables 31 and 32 each connected at one end thereof to a member 34 which is similar in all respects to a short section of the suspension track 24. The cables 31 and 32 are carried over pulleys 36 and 37 respectively secured to the ceiling 25 and are engaged at their ends opposite the member 34 with the drum of a hoisting windlass 39.

From the illustration and the above description, it will be observed that when either member 40 34 is carried to its uppermost position it forms, in effect, a continuous part of the suspension track 24. It will be further observed that the hoisting mechanism 27 is so located as to be adapted to place one of the ovens 20 over the article 15 as the article emerges from the spray booth 18 and that the hoisting mechanism 29 is so located as to remove the oven from the article at the end of the suspension track 24.

In Fig. 1a I have illustrated a platform 42 50 located above the track 10 and supported from the ceiling or from the floor at such a height as to permit the ovens carried by the suspension track 24 to pass over it, in such position that the platform will close the open bottoms of these ovens to conserve the heated air contained therein or to permit preheating of the air in an oven 55 just before the oven is placed over the article to be dried. It will be observed from the illustration in Fig. 1a that this platform 42 terminates at a sufficient distance from the booth 18 to permit 60 ovens to be lowered between the booth and the end of the platform and that the platform extends a sufficient distance along the track to cover the open bottoms of two or more ovens at the same 65 time. At this time it should also be understood that the trucks 12 are provided with solid or continuous platforms 44 which effectively close the open bottoms of the ovens 20 when the ovens are 70 in operative position upon the trucks. A short trolley 43 is provided above the platform 42 so that the heating elements of the oven may be energized to preheat the ovens while they rest upon the platform 42.

Referring now to Figs. 2 and 3, it will be observed that the form of my improved drying or

baking oven illustrated therein comprises, in general, an elongated, substantially rectangular, box-like structure having five complete walls and an open bottom. Preferably, the oven is composed of an inner structure 45 of sheet metal uniformly spaced from a similar outer structure 46 of the same material with suitable insulating material 47, such as asbestos fiber, compressed between the inner and outer structures. Suitable joints and bracing, such as the gusset plate 48, may be 10 used to render the oven rigid and durable. It is to be understood, however, that an oven comprising a single structure of sheet metal or other suitable material is within the scope of the invention.

The size and shape of my improved drying oven may also be altered to accommodate the oven to the size and shape of various articles of manufacture without in any way departing from the scope of the invention. Also, while I have illustrated 20 an oven adapted to enclose a single relatively large article, such as an automobile body, it is to be understood that a group of two or more smaller articles, such as casings for electric refrigerators, may be enclosed within one oven at the same 25 time.

Referring particularly to Fig. 2, it will be observed that I have provided on the upper portion of my improved oven a pair of lifting devices 50 and 50'. Each of these lifting devices comprises 30 a stem 51 secured at its lower end to the top of the oven and provided with a thin portion adapted to travel through the slot in the bottom portion of the suspension rail 24. At its upper end each stem 51 carries a transverse pin 52 upon the opposite end portions of which is mounted a pair of rollers 53 in end to end relation adapted to travel upon the bottom portion of the suspension rail 24, one upon each side of the slot. Referring to Figs. 1a and 1b, it will be observed that 40 these lifting devices 50 and 50' are utilized in combination with the members 34 to lower the oven over the article and raise it from the article by the engagement of the lifting devices with the members 34 as well as to support the oven on 45 the suspension rail 24 during the return of the oven from the end to the beginning of the drying section of the track 10.

Each of my improved ovens is also provided with an individual heating device such as the 50 electrical resistance heater indicated at 55 in Figs. 1a and 2. If desired, these heaters may be separately controlled as by the rheostat 57 and the internal temperature of each oven may be displayed by a temperature indicating device such as the thermometer 60 during the entire siccative action. It is also within the scope of the invention to apply automatic control devices to the heating elements of these portable ovens to automatically maintain a predetermined temperature or series of temperatures during the siccative action.

The numeral 62 indicates an electric fan which I have illustrated as let into one end of the oven and which is operative to circulate the air or 65 other gas contained within the oven, about the article which is being dried, or may force air from outside the oven into the oven if desired.

While, for the sake of clearness in the drawings, I have shown the oven heating device 55 70 located at a distance from the fan 62, it is to be understood that the heating element may be, and preferably is, combined with the fan, if a fan is used.

In Fig. 2 I have also illustrated a vent 65 for 75

permitting escape of used air from the ovens. In the first form of the invention, this vent may be opened or closed by manually controlled shutters 61. It is to be understood, however, that 5 these shutters 61 may be automatically controlled or may be omitted without departing from the scope of the invention.

In Fig. 4 I have illustrated the manner in 10 which an air humidifier, a drier, or a filter 10 may be applied to my improved drying oven in case it is desired to condition the drying air otherwise than by heating it. If a fan is used, the air humidifier or drier or filter 10 is preferably disposed between the fan 62 and the heating element 55 but may be located in any part of the oven without departing from the scope of the invention.

Referring back to Fig. 2, it will be observed that 20 I have provided suitable electrical connections and conductors for connecting the trolley 22 with the various electrically operated devices included in my improved oven. The numeral 72 generally indicates a trolley harp comprising a handle or supporting portion 73 and a contact carrying block 74. The contacts, not illustrated, carried by the block 74 are connected to flexible conductors 75 which are led through the upper portion of the oven and secured thereto by means of suitable insulators 77. From the insulators 30 77 the conductors are led to the rheostat, the heating element, the fan, and any other electrically operated device contained within the oven.

It will be noted that the flexible portions of 35 the conductors 75, between the block 74 and the insulators 77, are of sufficient length to permit a considerable latitude of movement to the trolley harp 72. The trolley harp handle 73 is detachably secured to the oven to hold the contact block 40 in contact with the trolley 22 by means of a bracket 80 secured to a side of the oven. Referring to Figure 1a it will be observed that the harp 72 is disconnected from the trolley 22 at the time the oven is first lowered over the wet coated article but may be connected as the oven moves 45 along with the truck 12 by manually inserting the handle 73 in the bracket 80.

In Figs. 5, 6, and 7, I have illustrated a somewhat modified form of drying oven and a different manner of handling the same from that illustrated in Figs. 1a, 1b, 2, and 3. In this modified form of the invention, instead of having trucks which run upon tracks mounted on the floor, I utilize platforms carried upon roller conveyors located at each end of the drying line, suspension tracks for supporting the ovens, and platforms during the drying or siccative process and returning the ovens from the end to the beginning of the drying line, a chain conveyor for 50 propelling the ovens and platforms along the drying line, and interlocking elements carried by the ovens and platforms to latch the platforms to the ovens during the siccative process.

In Fig. 5, I have illustrated an alternative 65 manner of handling the ovens from that illustrated in Figs. 1a and 1b. In this alternative manner, the objects of manufacture such as the automobile bodies as indicated at 15 are carried upon flat platforms 94 and emerge from the spray booth (not illustrated in this figure) upon a roller conveyor 100 mounted on the floor 111 at the beginning of the drying line. At the end of the drying line is a similar roller conveyor 101 and between the two roller conveyors is a chain conveyor 103. Overlying the chain conveyor and

extending somewhat beyond each end thereof are a pair of suspension tracks 105 and 106 of I-section shown in end view in Fig. 6. These tracks may be supported from the floor or the ceiling by suitable means such as the vertical hangers 5 108. Immediately above the suspension tracks 105 and 106 at a vertical distance thereabove somewhat greater than the height of the drying ovens is a second pair of suspension tracks indicated at 124 also secured to the ceiling as by 10 hangers 109. At each end of the suspension tracks is a hoisting device generally indicated at 127 and 129. Each hoisting mechanism comprises two pair of flexible cables as indicated at 131 and 132, each cable of each pair being connected at one end thereof to a member 134, these members being similar in all respects to a short section of the suspension tracks. The cables are carried over pulleys as indicated at 136 and 137 secured to the ceiling 125 and are engaged at 20 their ends opposite the members 134 with the drums of the hoisting windlasses as indicated at 139.

From this description, it will be observed that 25 the members 134 may be moved by means of the hoisting mechanisms from one to the other of two operative positions in which they constitute a continuation of the track 106 or the track 124 and that by means of these members and the 30 associated hoisting mechanisms the ovens may be shifted from the upper to the lower suspension tracks at the beginning of the drying process and from the lower to the upper track at the end of the drying process. During the drying process, the ovens are moved along the lower track by the 35 chain conveyor 103 and at the end of the process the ovens may be returned manually or otherwise along the upper track 124.

The hoisting mechanisms overlie the respective 40 roller conveyors 100 and 101 so that the platforms 94 are picked up from and set down on the rollers at the beginning and the end of the drying process. The platforms are not returned with the ovens but carry the articles on to the end of the production line, of which the drying or 45 siccative process constitutes a part, and are returned to the head of the production line.

In combination with the above described method of handling the ovens, I have provided a somewhat modified form of oven 140 particularly illustrated in Figs. 6 and 7. It is to be understood, however, that the different ovens illustrated and described are completely interchangeable and may be adapted to the different methods of handling by simply installing the proper carrying and current supplying devices. 50

The oven 140 illustrated in Figs. 5 and 6 preferably comprises an inner and outer wall structure with insulating material between the two walls as illustrated in Fig. 3. In addition to the 60 construction illustrated in Figs. 2 and 3, the oven 140 is provided with side walls 141 which slope outwardly from top to bottom to provide a space between the lower edge of each side wall and the adjacent edge of the platform 94. These 65 spaces may be closed by movable closure members 142 secured to the end walls of the hood by pivoted links 144 and 145.

I have provided indentations 150 in the upper portion of the oven 140 at each end thereof and 70 in one of these indentations I have mounted an air conditioning device generally indicated at 152 comprising an air heater and drier 155, a fan 162, and a motor 163 for operating the fan. I have also provided ducts 164 for conveying the heated 75

air from the heater 155 to the central portion of the oven. A vent 165 is provided in the upper portion of each oven to permit the escape of air therefrom.

5 For purposes of carrying the empty oven or the oven and platform and article during the siccative action, I have provided carriers 170 secured to the oven on the upper portion of the sides thereof and containing rollers 172 which 10 run upon the tracks 106 or 124, there being two such carriers on each side of each oven.

In order that electric current may be supplied to the oven during the siccative action or the preheating period, I have provided a side 15 bracket 180 adapted to support a handle 173 provided at its upper end with a block or trolley 174 adapted to contact an electrical conductor 122.

Referring to Fig. 6 it will be observed that each 20 of the platforms 94 is provided at its ends with hooks 184 and that each of the ovens 140 is provided at each of its ends with a substantially U-shaped bar 185 pivotally secured to the oven by brackets 186 and terminating in bent-over ends 187 adapted to engage the hooks 184 to releasably secure the ovens 140 to the platforms 94 so that the oven, platform and article may be 25 picked up as a unit by the hoisting mechanism and moved as a unit along the lower suspension track during the siccative action.

30 The method of operation of the device is substantially as follows: as each wet coated article emerges from the spray booth 18 an oven is lowered over the article and permitted to rest upon the platform carrying the article thus together 35 with the platform, forming a tight enclosing space only slightly larger than the article. The trolley harp is then connected to the trolley by inserting the handle in the bracket. The heating element and fan are thereby energized and 40 the siccative action proceeds for the specified length of time. At the end of this time, or when the trolley harp has reached a point adjacent to the end of the trolley the handle is removed from the bracket and the oven is removed from the 45 article by the hoisting mechanism and returned along the suspension track to the proximity of the spray booth 18. As the oven rests above the platform 42 the air within the oven may be pre-heated preparatory to repeating the above cycle.

50 It will be understood that while in general, uniform drying conditions will be maintained in all of the ovens, the drying conditions in any individual oven may be manually or automatically varied if desired to meet particular siccative requirements.

In Figs. 8 and 9 I have illustrated still another method of handling my improved drying ovens and an oven and platform specially adapted to this last method.

60 In Fig. 8 I have illustrated a somewhat different type of industrial building from that illustrated in Figs. 1a, 1b, and 5. In the building illustrated in Fig. 8 I have shown a floor 211 and a ceiling 225 but have shown the central portion of 65 this building extended upwardly to accommodate a traveling crane generally indicated at 230. This crane comprises a beam 232 supported at its ends by means of rollers 234 upon tracks 235 which in turn are supported upon the sides of the building by brackets 231. A hoist or lift device 238 is supported on the upper surface of the beam 232 by rollers 240 and the operation of the crane is controlled from an operator's cage 242. A cable 70 75 250 extends downwardly from the lifting device

238 and is provided at its lower end with a hook 252 for a purpose to be presently described.

A spraying booth 18 is located at one side of the elevated central portion of the building and from this booth the freshly painted objects such 5 as the automobile bodies 15 carried upon platforms 94 emerge upon the rollers 200. A second group of rollers 201 is located at the continuation of the production line on the opposite side of the crane space from the rollers 200. 10

When the platform 94 carrying the wet coated article 15 emerges from the spray booth 18 onto the rollers 200, the crane is operated to impose an oven over the article. The oven is latched to the platform by a suitable locking device such as 15 that described in connection with the construction illustrated in Figs. 5, 6, and 7. The oven, platform, and article of manufacture may then be picked up by the crane and moved to a location 20 where drying or siccative action may be carried on. 20

The drying hood used is similar to that shown in Figs. 6 and 7 except that electrical harp 173 and bracket 180 are replaced by electrical outlets 255 in Fig. 8 in the platform, and carriers 170, rollers 172, track 106 and ceiling brackets 108 in Figs. 6 25 and 7 are replaced by floor rests 260. The drying oven is also provided in the top thereof with a ring bolt 265 with which the hook 252 may be engaged to lift the oven.

On the floor of the portion of the building containing the crane 230, I have located a plurality of positions arranged to receive the ovens 140, platforms 94, and the articles 15 as units and equipped with electrical outlets 270 to cooperate with the outlets 255. It is to these positions that 35 crane 85 transfers the oven units from rollers 200, so that the siccative action may occur, while the oven units are upon floor rests 260. It will be noted that one important distinction between the form of the invention illustrated in Figs. 1a, 1b, 40 2, and 3 and Figs. 5, 6, and 7 and that illustrated in Figs. 8 and 9 is that in the first two forms the drying or siccative action takes place while the ovens are in motion while in the last form the drying or siccative action takes place while the ovens 45 are stationary.

In Fig. 10 I have illustrated still another modification of oven 140 Figs. 6 and 7 or oven 20 Figs. 2 and 3. This oven is exactly similar in design to either oven 20 or oven 140, except that either one 50 end 300 or one side is hinged by a single hinge 302 at its uppermost edge or by a plurality of hinges disposed at different vertical levels, so as to permit of the removal of article 15 without the necessity of raising the hood from the level at which the 55 siccative action occurs. This type of oven is of particular advantage in small installations such as repaint shops where it is not desirable to install extensive oven handling equipment such as is illustrated in Figs. 1a and 1b, 5, and 8, and in 60 65 which it is desired, at the same time to simulate factory conditions in the drying or siccative action.

While I have illustrated and described certain specific mechanical embodiments of the idea of 65 my invention it is to be understood that the invention is not limited thereto but that such changes in the size, shape, and arrangement of parts may be resorted to as come within the scope 70 of the subjoined claims.

Having now described my invention so that others skilled in the art to which it appertains may fully understand the same, what I desire to secure by Letters Patent is as follows:

1. In combination with a production line adapted to carry a train of wet coated articles through a siccative process a plurality of portable drying ovens comprising, open bottom hoods adapted to be applied to said articles individually without interrupting the progress of said train, means for applying said ovens to said articles at the beginning of said siccative process, means for removing said ovens from said articles at the end of said siccative process, means for returning said ovens from the end to the beginning of the siccative process portion of said production line, and means for preheating the air contained in each of said ovens immediately before said oven is applied to said article.
2. In combination with a production line adapted to carry a train of wet coated articles through a siccative process, a plurality of portable drying ovens comprising, open bottom hoods adapted to be applied to said articles individually without interrupting the progress of said train, means for applying said ovens to said articles at the beginning of said siccative process, means for removing said ovens from said articles at the end of said siccative process, means for returning said ovens from the end to the beginning of the siccative process portion of said production line, and means for conserving the heated air or gases contained in each of the said ovens after the siccative process has been completed.
3. Apparatus for performing siccative action on articles of manufacture comprising, a plurality of separate article supports movable along a predetermined path, a plurality of portable drying inclosures cooperating individually with said supports to provide separate compartments for said articles during said siccative action, individual air heating and circulating means incorporated in each inclosure for carrying on said siccative action, means for transporting said ovens and article supports, and means for supplying energy to said individual air heating and circulating means along the path over which said ovens and article supports are transported.
4. The method of performing siccative action on wet coated articles of manufacture which comprises, moving said articles in series along a predetermined path, enclosing each of said articles in succession, applying heat to each of said articles individually, moving said series while the articles are so enclosed and heated, and finally, uncovering each of said articles in succession.
5. The method of performing siccative action on wet coated articles of manufacture which comprises, moving said articles in sequence along a predetermined path, applying separate ovens to said articles consecutively as said articles progress along said path, applying heat individually to the interiors of said ovens as the ovens and included articles progress along said predetermined path and exposing said articles at the completion of said siccative action.
6. The method of performing siccative action on wet coated articles of manufacture which comprises, moving said articles in series along a predetermined path, applying a separate oven to each article in succession without interrupting the progress of said series, applying heat to each oven while said oven and the included article are being moved as a unit along said predetermined path, and removing said ovens from said articles in succession as the siccative action on the respective articles is completed.
7. The method of performing siccative action on wet coated articles of manufacture which comprises, moving said articles in series along a predetermined path, enclosing said articles consecutively in separate ovens, moving each article and enclosing oven as a unit along said predetermined path, applying heat to each oven individually while it is being moved along said path, controlling the heat applied to each oven to carry on said siccative action in desired stages, and removing said ovens from said articles at the completion of the siccative action on the enclosed article.
8. The method of performing siccative action on wet coated articles of manufacture which comprises, moving said articles in series to a predetermined point, enclosing each article separately in a portable oven, moving each oven and included article as a unit away from said predetermined point, applying heat interiorly only of each enclosing oven to carry on said siccative action, returning said ovens and included articles to a predetermined point, and finally removing each article from the enclosing oven at said last-named predetermined point.

ROBERT R. LUNDY. 50
